UNITED STATES PATENT OFFICE

120,149

DESIGN FOR A SHOE

Martin M. Tishler, Roxbury, Mass.

Application February 5, 1940, Serial No. 90,022

Term of patent 3½ years

To all whom it may concern:

Be it known that I, Martin M. Tishler, a citizen of the United States, residing at Roxbury, in the county of Suffolk and Commonwealth of Massachusetts, have invented a new, original, and ornamental Design for a Shoe, of which the following is a specification, reference being had to the accompanying drawing, forming a part thereof.

In the drawing:

The figure is a side perspective view of a shoe showing my new design in which the counter is

incorporated showing the side thereof, the dominant feature of which is the decrease in height of the counter from the ankle strap to the back of the heel in combination with the cross strap across the top of the rear of the heel. The opposite side of the shoe presents substantially the same appearance as the side shown except that there is no buckle thereon.

I claim:

The ornamental design for a shoe, as shown and described.

MARTIN M. TISHLER.
